WILLIAM J. NEWTON, OF BRIDGEPORT, CONNECTICUT, ASSIGNOR TO HARVEY HUBBELL, INCORPORATED, OF BRIDGEPORT, CONNECTICUT, A CORPORATION OF CONNECTICUT.

SWITCH COVER AND SUPPORT.

Application filed January 13, 1920. Serial No. 351,269.

To all whom it may concern:

Be it known that I, WILLIAM J. NEWTON, a citizen of the United States, residing at Bridgeport, county of Fairfield, State of Connecticut, have invented an Improvement in Switch Covers and Supports, of which the following is a specification.

At the present time various forms of locking mechanisms for switches, especially 10 on automobiles, as for locking the magneto, batteries, or the lighting system, are in use. It is usual in these mechanisms, so far as I am aware, to lock the switches themselves, either singly or jointly.

15 It is the object of this invention to provide a switch cover and support having in its face plate an opening for what I term a disappearing door because when open it is moved to the rear of the face plate practically out of sight although it does not disappear literally, because when open its front edge projects a small distance forwardly of the face plate so that it may be grasped and pulled to closed position. This 20 door, when locked, encloses and conceals the switches, and when unlocked, springs from its position so that the switches are accessible and may be manipulated in the usual manner. The invention thus provides a 25 means for concealing the switch mechanisms, for preventing access to them by tamperers, and for enclosing them from flying particles, and to attain these desirable ends I provide a locking mechanism of simple structure for the so-called disappearing door.

With the above and other objects in view the invention will now be fully described and hereinafter specifically claimed.

40 In the accompanying drawing forming a part of this specification.

Figure 1 is a front elevation of the novel switch box with the disappearing door in closed position;

45 Figure 2 a side elevation corresponding with Figure 1;

Figure 3 a front elevation with the disappearing door in open or disappearing position;

50 Figure 4 a side elevation corresponding with Figure 3;

Figure 5 a section on the line 5—5 in Figure 3;

Figure 6 a rear elevation with the door closed; 55

Figure 7 a rear elevation with the door open; and

Figure 8 is a perspective view showing in detail certain of the elements of the invention, disassembled. 60

20 denotes a plate which carries the switches and is secured at its opposite ends to plates 25 which are in turn secured to the face plate 21. The face plate 21 has an opening 22 therein, in which is mounted the so-called disappearing door 23. The switch mechanisms 24 are secured to the plate 20 by means of screw bolts 24'. These mechanisms are of conventional form so are not shown in detail. The face plate is spaced 65 from the plate 20 and so located that the levers 24" for the switch mechanisms are directly beyond the opening in the face plate and when the door is in open position they will be accessible, as clearly shown 70 in Fig. 3. The member 20' is a narrow plate closing the opening between the lower edge of plate 20 and the rear of the face plate. 75

The plates 25 also form brackets or supports for the door and locking member and the door is provided with ears 26, each of which comprises a strip of metal bent outward and back upon itself as indicated at 27, thus providing parallel arms as indicated at 28 and 29. The brackets pass between the parallel arms of the ears, and are pivoted thereto by pivot pins 30 which pass through the inner ends of the brackets and the inner lower corners of the parallel 85 arms. The pivot pins have thereon coil springs 31, the ends of which are attached to the parallel arms and to the brackets, respectively, as indicated at 32 and 33. The outer lower end of one of the arms 29 is 90 provided with a catch 34 which is engaged by a latch 35 on a substantially U-shaped locking member 36 which will be described. When the catch is engaged by the latch, the door will be in its closed position and 95 the bent portions of the ears will lie closely adjacent the upper edges of the brackets, 100

as clearly shown in Figure 2. When the catch is released, the coil springs will swing the door to its open or so-called disappearing position, as clearly shown in Figures 5, 4, and 5.

The substantially U-shaped locking member comprises a flat connecting member 37, a broad flat arm 38, a cut away arm 39, a flat bridge 40 between the arms, and the 10 latch, which, as indicated, is on the cut away arm. The cut away arm is provided with small ears 41 near its lower end, and on the lower end of the bracket which carries the arm with the catch are small ears 15 42. Ears 41 are set between ears 42, and the pivot pin 43, passing through perforations in the two sets of ears, pivots the U-shaped locking member to the bracket. A coil spring 44 on the pivot pin, having ends 20 bearing against the switch box and the lower end of the cut away arm, normally holds the latch in engagement with the catch, as will be readily understood.

In the face plate and adjacent the upper 25 end of arm 38 is a lock 45 having a hub 46 and a barrel 47, the latter being provided with a cam, as indicated at 48, which is arranged to turn with the barrel when the latter is operated by a key.

30 When the door is in its closed and locked position and access to the switch levers is desired, a key is inserted in the lock and the barrel is rotated. The cam carried thereby, being made a proper length, pushes the upper inner wall of arm 38, and hence the locking member, against the action of spring 44, a sufficient distance to release the latch from the catch. Coil springs 31 immediately swing the door to its open or disappearing position. When the cam has turned past arm 38, coil spring 44 forces the locking member toward the switch box and the latch rests against the bracket. When the 35 front end of the door is manually grasped and the door is drawn to its closed position over the opening in the face plate, the catch rides past the latch and the shoulders of the catch and latch engage each other and thus lock the door in its closed position.

40 50 It is to be understood that I have shown one form of carrying my invention into effect and that such changes may be made in the structure of the switch cover and support as are warranted by the scope of the appended claims.

55 What I desire to claim is:

1. A device of the character described comprising a face plate provided with an opening, a spring controlled door provided 60 with ears having parallel arms, brackets to which the parallel arms are pivoted, a catch carried by one of said parallel arms, a locking member carried by one of said brackets and having a latch to engage the catch to

hold the door in the opening, means for releasing the latch from the catch, and means for swinging the door from the opening.

2. A device of the character described, comprising a face plate provided with an opening, a spring controlled door provided 70 with ears having parallel arms, brackets to which the parallel arms are pivoted, a catch carried by one of said parallel arms, a locking member carried by one of said brackets and having a latch to engage the catch to hold the door in the opening, a lock provided 75 with a cam adapted to release the latch from the catch, and means for swinging the door from the opening.

3. A device of the character described comprising a face plate provided with an opening, a spring controlled door provided with ears having parallel arms, brackets to which the parallel arms are pivoted, a catch carried by one of said parallel arms, a locking member carried by one of said brackets and having a latch to engage the catch to hold the door in said opening, a lock provided with a cam adapted to release the latch from the catch, and springs arranged to swing the door from the opening.

4. A device of the character described, comprising a face plate provided with an opening, a spring controlled door provided with ears having parallel arms, brackets to which the parallel arms are pivoted, a catch carried by one of said parallel arms, a spring pressed locking member carried by one of said brackets and having a latch to engage the catch to hold the door in the opening, a lock provided with a cam adapted to engage the spring pressed locking member to release the latch from the catch, and springs arranged to swing the door from the opening.

5. A device of the character described, comprising a face plate provided with an opening, a spring controlled door for the opening, a pivotal support for the door at the rear of the face plate, a spring pressed locking member for holding the door in the opening, a lock operated cam to release the locking member from the door, and springs tending to swing the door from the opening to the rear of the face plate on said pivotal support whereby when the cam releases the locking member, the door swings from the opening, and when the door is manually drawn back over the opening, the spring pressed locking member grips the door and holds it.

6. A device of the character described, comprising a face plate provided with an opening, switch mechanism carried by the face plate and accessible through said opening, a door for the opening, and means for moving the door from the opening substantially to the rear of the face plate and out of alignment with the switch

mechanism with the exception of a portion adapted to be manually grasped for closing the door.

7. In a device of the character described, a face plate provided with an opening, a door for said opening, means pivotally mounting said door for movement so that in one extreme position it lies with its face substantially flush with one face of the face plate and in the other in a position to uncover said opening with a portion of one edge projecting on the face side of said plate, means biasing said door to the latter position and means including a stationary portion on the plate for locking the door in its first named position.

8. A device of the character described, comprising a face plate provided with an opening, switch mechanism in the rear of the face plate and accessible through said opening, a door for the opening, means for supporting the door in the opening to close the same, said means being so arranged that the door may be opened by being moved to a position substantially at the rear of the face plate and at one side of the opening with a portion thereof in a position to be manually grasped at the opening in the face plate for closing the door.

In testimony whereof I affix my signature.

WILLIAM J. NEWTON.
